UNITED STATES PATENT OFFICE.

GEORGE W. WELLS, OF SOUTHBRIDGE, MASSACHUSETTS.

EYEGLASS-SPRING.

SPECIFICATION forming part of Letters Patent No. 729,464, dated May 26, 1903.

Application filed January 20, 1903. Serial No. 139,840. (No model.)

To all whom it may concern:

Be it known that I, GEORGE W. WELLS, a citizen of the United States, residing at Southbridge, in the county of Worcester and State 5 of Massachusetts, have invented certain new and useful Improvements in Eyeglass-Springs, of which the following is a specification.

My invention relates to eyeglass-springs made of flat metal; and the object of my invention is to make an improved eyeglass-spring of reduced width through the central portion and with widened ends to fill the recess in the head of the eyeglass-post.

In making my improved eyeglass-spring I preferably take a strip of narrow flat metal and cut it into blanks of the desired length and of such a width at the ends that when the ends are bent edgewise to extend alongside of and contiguous to the main part of 20 the strip the width of the bent ends will nearly fill the recess in the head of the eyeglass-post. I bend the extreme ends edgewise on the same side of the strip to cause them to extend alongside of and substantially parallel to the 25 main body of the strip. The bending of the ends makes the metal a little thicker at the bent portion, and the bent ends are placed in a die or holder of proper shape and hammered or swaged to flatten the ends to make them 30 the proper width, so that they will substantially fill the recess in the head of the eyeglass-post. The amount of the flattening of the ends is controlled by the size of the die. The free end of the bent portion is left 35 disconnected from the main portion, leaving the ends partially slit centrally. A hole is drilled or punched in the widened ends for the holding-screw.

My invention consists in certain novel features of construction of my improvements in eyeglass-springs of flat metal, as will be hereinafter fully described.

Referring to the drawings, Figure 1 is a front perspective view of an eyeglass-spring embodying my improvements. Fig. 2 is a detached end view looking in the direction of arrow *a*, Fig. 1. Fig. 3 shows a flat strip of metal or a blank from which the spring is made. Fig. 4 shows the blank in Fig. 3 with 50 the ends bent edgewise to make them wider,

and Fig. 5 shows the blank in Fig. 4 after the holes are punched in the widened ends.

In the accompanying drawings, 1 is a blank or strip of flat metal of the desired length and width from which my spring is made. 55 Each end of the blank 1 is bent edgewise on the same side of the blank, as shown in Fig. 4, thus doubling the width of the blank at its attaching ends. The double width of the blank at its ends makes it wide enough to 60 substantially fill the recess in the post of the eyeglass. The bent ends 1' of the blank 1 are then preferably hammered or swaged to compress and flatten the metal and cause the ends to closely fill the recess in the eyeglass- 65 post and prevent their working from side to side. In hammering or swaging the bent ends 1' they are placed in a die or holder of suitable shape and size. The swaging of the bent ends 1' does not close the slit or opening 70 between the bent ends and the main part of the blank, so that the bent ends may and will have a tendency to spring out or move away slightly from the main part of the blank, and thus tend to keep the ends of the eyeglass- 75 spring tight in the post. A hole or perforation 2 is punched in the bent ends 1' of the blank, as shown in Fig. 5, and then the blank is bent into the form of the finished spring, 80 as shown in Fig. 1.

I am aware that it is not new to enlarge or widen the attaching end of a flat eyeglass-spring by stamping or cutting the blank of narrower width between the attaching ends; but I am not aware that prior to my invention the enlarged or widened ends of a flat eyeglass-spring have been made from a blank by turning or bending the ends of the blank 85 edgewise to double the width of the blank at its ends with the additional width all on one 90 side or edge of the blank.

In my improved construction of eyeglass-springs with widened attaching ends narrower strips of metal can be used and there is no loss of material, as in the ordinary construction above referred to, in which the blank is trimmed or cut on each edge between its ends to leave the widened ends with each edge of the ends extending beyond the edges 95 of the main portion of the spring.

I have used the term "eyeglass-spring;" but it will be understood I intend to include herein what are also termed "bridges," "bridge-pieces," or "bows" of eyeglasses and 5 spectacles.

It will be understood that the details of construction of my improved eyeglass-spring may be varied, if desired.

I have used the words "flat metal;" but I 10 intend to include under said words flattened metal or oval shape in cross-section or partially cylindrical shape.

Having thus described my invention, what I claim as new, and desire to secure by Letters 15 Patent, is—

1. An improved article of manufacture, an eyeglass spring or bridge, of flat metal, having its ends widened by bending the ends edgewise to extend substantially parallel

with the main portion of the spring, substantially as shown and described. 20

2. An eyeglass spring or bridge, of flat metal, with its ends of substantially double the width of the main portion, and perforated and partially disconnected from the main 25 portion, substantially as shown and described.

3. An eyeglass spring or bridge, of flat metal, having ends of substantially double the width of the main portion, with the additional width all on one side or edge of the 30 spring, and the ends perforated and partially slit centrally, substantially as shown and described.

GEORGE W. WELLS.
